UNITED STATES PATENT OFFICE

ALEXANDER J. WUERTZ, OF WILMINGTON, DELAWARE, ASSIGNOR TO E. I. DU PONT DE NEMOURS & COMPANY, OF WILMINGTON, DELAWARE, A CORPORATION OF DELAWARE

PRODUCTION OF BENZANTHRONE

No Drawing.

Application filed August 19, 1927. Serial No. 214,221.

This invention relates to the production of benzanthrone from anthraquinone. It relates more particularly to a process which may be carried out in substantially a single step having many valuable features.

The synthesis of benzanthrone is usually effected by condensing anthraquinone with glycerine by means of sulphuric acid in the presence of aniline sulphate, or by condensing anthranol with glycerine in a medium of sulphuric acid. The technical method most commonly used consists in a reduction of anthraquinone in sulphuric acid solution by means of copper or aluminum powder at a low temperature and then effecting a condensation of the reduction product (anthranol) with glycerine to form benzanthrone. In the final analysis this procedure is a condensation of anthranol and glycerine. These methods are somewhat objectionable because of their comparatively low yields probably due to over-reduction, etc.

It is an object of the present invention to prepare benzanthrone from anthraquinone to obtain maximum yields. It is a further object to carry out the reduction step of the process by means of the cheaper iron dust in place of the usual copper or aluminum.

30

35

Other objects will be apparent from the description.

The present invention comprises the synthesis of benzanthrone by a substantially simultaneous reduction of anthraquinone and condensation of the reduction product with glycerine, both reactions being carried out in a medium of sulphuric acid.

45 Without restricting the invention thereto, the following will serve as an example of procedure in accordance therewith:

100 parts of anthraquinone are dissolved in 93-100% sulphuric acid at room temperature. The solution is then diluted with

cold water until the acidity is brought down to 80-83% H_2SO_4 . This dilution insures almost a complete precipitation of the anthraquinone. The temperature is then raised to 110-115° C. While maintaining this temperature 40-45 parts of iron dust (60-150 mesh) and 80-90 parts of distilled glycerine are slowly added simultaneously at such a rate that both ingredients are introduced into the reaction mass in a period of from two to four hours. The temperature is then raised slowly to 118-120° C. (about one-half to one hour) and maintained at this point until no unchanged anthraquinone is shown by the usual tests. When the conversion of the anthraquinone to benzanthrone is complete, the charge is drowned in a sufficient amount of cold water to bring the acidity to 5-8% of H_2SO_4 and the precipitated benzanthrone is filtered off, washed, and dried.

In the above example, the anthraquinone is reduced to hydroxy-anthrone which immediately reacts with the glycerine to form benzanthrone. The elimination of the reduction product prevents excessive reduction and therefore results in a more uniform final product. The chemical reactions involved are as follows:

The final chemical reaction taking place is as follows:

As is well known, hydroxy-anthrone and anthraquinol are isomeric and behave in an 100

identical manner in the conversion to benzanthrone. In the reduction of anthraquinone, according to the present invention, both isomers are produced, one being changed to the other by a readily reversible reaction.

The present process permits the use of iron dust in place of copper, aluminum or aniline sulphate. This is a distinct economic advantage, although the present process will operate very efficiently when copper or aluminum is used in place of the iron.

In the usual processes heretofore used, benzanthrone is produced from anthranol instead of hydroxy-anthrone. The reduction of the anthraquinone is represented by the following:

When anthranol is used, low yields of benzanthrone are obtained, usually about 85-90% of theory. The yield according to the present invention is nearly 100% of the theory and the purity of the product is better than that obtained by the known technical processes. The use of iron dust under the above conditions presents a great economic advantage in that it is possible to reduce the consumption of glycerine approximately 40% of the usual requirement.

The benzanthrone obtained according to the present process has a freezing point of 169-170° C. and a purity of 90-93%. It is highly valuable for the synthesis of a large number of vat colors commonly known as the benzanthrone vat dyes.

It will be understood that the operation of the process is not limited to the specific details described. For instance, the dissolving of the anthraquinone in 93-100% sulphuric acid and subsequent dilution offers the most convenient practice for obtaining the anthraquinone in a finely divided state and suspended in the proper concentration of sulphuric acid. An alternative method of preparing the charge consists in dissolving the anthraquinone in sulphuric acid, precipitating by drowning, filtering and then slurring the press cake with sulphuric acid and adjusting the acid to the proper concentration. While this is one of the preferred conditions, it is obvious that other methods may be used to obtain the same result. The dilution of the sulphuric acid to 80-83% strength is usually preferred for the present reaction,

whether iron, copper or aluminum is used as the reducing agent. Lower or higher strength of acid will produce benzanthrone but not so satisfactorily as the preferred range.

The temperatures used in the present process are susceptible of some variation, although those given are the preferred ones. The reduction is carried out at a temperature of 110-115° C. as this temperature is about that at which the glycerine is converted to acrolein which in turn enters into the reaction with hydroxy-anthrone or anthraquinol to form the benzanthrone. If the reduction is carried out at lower temperatures, the hydroxy-anthrone and anthraquinol will accumulate and be converted to anthranol and anthrone, the very thing which the present process attempts to obviate. The present process makes use of temperatures between 118-120° C. to finish the reaction in order to assure complete conversion. While these temperatures and higher may be used at the start of the reaction, it is found that these temperatures will result in too rapid a reaction and will not permit proper control of the process.

Suitable changes may be made in carrying out the process without departing from the spirit and scope of the invention, except as limited by the appended claims.

I claim:

1. The process for producing benzanthrone which comprises suspending anthraquinone in concentrated sulphuric acid and heating the suspension while simultaneously adding glycerine and a metallic reducing agent from the group consisting of iron, copper and aluminum, at a temperature of 110-120° C.

2. The process for producing benzanthrone which comprises suspending anthraquinone in concentrated sulphuric acid and heating the suspension while simultaneously adding glycerine and a metallic reducing agent from the group consisting of iron, copper and aluminum, at a temperature of 110-115° C.

3. The process for producing benzanthrone which comprises suspending anthraquinone in concentrated sulphuric acid and heating the suspension while simultaneously adding glycerine and iron at a temperature of 110-120° C.

4. The process for producing benzanthrone which comprises suspending anthraquinone in concentrated sulphuric acid and heating the suspension while simultaneously adding glycerine and iron at a temperature of 110-115° C.

5. The process for producing benzanthrone which comprises reducing anthraquinone by means of a metallic reducing agent from the group consisting of iron, copper and aluminum, and condensing the reduction product with glycerine, both reactions being carried out simultaneously in a sulphuric acid medi-

um heated to temperatures of about 110°-120° C.

6. The process for producing benzanthrone which comprises reducing anthraquinone by means of iron, and condensing the reduction product with glycerine, both reactions being carried out simultaneously in a sulphuric acid medium heated to temperatures of about 110-120° C.

10 7. The process for producing benzanthrone which comprises suspending anthraquinone in 80-83% sulphuric acid and heating the suspension while simultaneously adding glycerine and a metallic reducing agent of the group consisting of iron, copper and aluminum, the temperatures of the suspension being maintained at about 110-120° C.

15 8. The process for producing benzanthrone which comprises suspending anthraquinone in 80-83% sulphuric acid and heating the suspension while simultaneously adding glycerine and iron, the temperatures of the suspension being maintained at about 110-120° C.

20 9. The process for producing benzanthrone which comprises suspending anthraquinone in concentrated sulphuric acid, reducing the anthraquinone with a finely divided metal taken from the group consisting of iron, copper and aluminum to form hydroxy-anthrone and anthraquinol, and reacting upon the reduction products with glycerine substantially as soon as they are formed in the sulphuric acid suspension which is maintained at temperatures of about 110-120° C.

25 10. The process for producing benzanthrone which comprises suspending anthraquinone in concentrated sulphuric acid, reducing the anthraquinone with finely divided iron to form hydroxy-anthrone and anthraquinol, and reacting upon the reduction products with glycerine substantially as soon as they are formed in the sulphuric acid suspension which is maintained at temperatures of about 110-120° C.

30 11. In the process of making benzanthrone, the step which comprises reducing anthraquinone, in the presence of glycerine, and in a sulphuric acid medium of greater than about 80% strength, and maintained at temperatures of about 110-120° C. by means of a metal taken from the group consisting of aluminum, copper and iron.

35 12. In the process of making benzanthrone, the step which comprises reducing anthraquinone, in the presence of glycerine, and in a sulphuric acid medium of greater than about 80% strength, and maintained at temperatures of about 110-120° C. by means of iron.

40 13. In the process of making benzanthrone, the step which comprises reducing anthraquinone, in the presence of glycerine, and in a sulphuric acid medium of greater

than about 80% strength, and maintained at temperatures of about 110-120° C. by means of a finely divided metal taken from the group consisting of aluminum, copper and iron.

45 14. In the process of making benzanthrone, the step which comprises reducing anthraquinone, in the presence of glycerine, and in a sulphuric acid medium of greater than about 80% strength, and maintained at temperatures of about 110-120° C. by means of finely divided iron.

50 15. In the process for producing benzanthrone, the step which comprises reducing anthraquinone with finely divided iron and condensing the reduction product with glycerine, both reactions being carried out simultaneously in a sulphuric acid medium of greater than about 80% strength and maintained at temperatures of about 110-120° C.

55 16. In the process for producing benzanthrone, the step which comprises reducing anthraquinone with finely divided iron and condensing the reduction product with glycerine, both reactions being carried out simultaneously in a sulphuric acid medium of greater than about 80% strength and maintained at temperatures between 110-115° C.

60 17. The process of producing benzanthrone, which comprises suspending anthraquinone in a sulphuric acid medium, simultaneously adding glycerine and a reducing agent consisting only of a metallic substance from the group consisting of iron, copper and aluminum, and heating the suspension.

65 18. The process of producing benzanthrone, which comprises suspending anthraquinone in a sulphuric acid medium, simultaneously adding glycerine and a reducing agent consisting only of iron, and heating the suspension.

In testimony whereof I affix my signature.

ALEXANDER J. WUERTZ.
